E. W. BULLARD.

BRACE HEAD.

APPLICATION FILED SEPT. 13, 1920.

1,388,921.

Patented Aug. 30, 1921.

*Edwin W. Bullard Inventor
By assignment and sale of
Seymour and Bull Company*

UNITED STATES PATENT OFFICE.

EDWIN W. BULLARD, OF WHITNEYVILLE, CONNECTICUT, ASSIGNOR TO WINCHESTER REPEATING ARMS CO., OF NEW HAVEN, CONNECTICUT, A CORPORATION.

BRACE-HEAD.

1,388,921.

Specification of Letters Patent. Patented Aug. 30, 1921.

Application filed September 13, 1920. Serial No. 409,851.

To all whom it may concern:

Be it known that I, EDWIN W. BULLARD, a citizen of the United States, residing at Whitneyville, in the county of New Haven and State of Connecticut, have invented a new and useful Improvement in Brace-Heads; and I do hereby declare the following, when taken in connection with the accompanying drawings, and the characters of 10 reference marked thereon, to be a full, clear, and exact description of the same, and which said drawings constitute part of this application, and represent, in—

Figure 1, a view in vertical central section 15 of a brace head constructed in accordance with my invention and shown as applied to the upper end of the crank of a brace shown in elevation and broken away.

Fig. 2, a reverse plan view of the head 20 with the crank in transverse section on the line 2—2 of Fig. 1.

Fig. 3, a detached broken view in elevation of the upper end of the crank.

Fig. 4, a detached view, partly in elevation 25 and partly in section, of the assembling-cup.

Fig. 5, a corresponding view of the ball-cup.

Fig. 6, a reverse plan view thereof.

Fig. 7, a view, partly in elevation and 30 partly in section, of the retaining-ring.

Fig. 8, a reverse plan view thereof.

Fig. 9, a broken view, partly in elevation and partly in section, of one of the modified forms of my improvement.

Fig. 10, a reverse plan view thereof.

My invention relates to an improved head for bit braces, drill braces and similar tools, the object being to produce a simple, durable and easy-running structure.

With these ends in view, my invention 40 consists in a brace head having certain details of construction and combination of parts, as will be hereafter described and pointed out in the claim.

In carrying out my invention as herein 45 shown, I employ a one-piece assembling-cup comprising a tapered sleeve 11 and flange 12, the sleeve fitting over the upper end of the crank 13 and the flange having its edge 14 spun into an annular recess 15 formed near 50 the inner edge of the periphery of the wooden brace head body 16 of the ordinary

flattened form. The said body has a central, circular recess 17 entering its inner face and receiving a conical-ended ball-cup 18, the 55 edge of which rests upon the flange 12 of the assembling-cup near the point where the said flange merges into the sleeve 11, whereby the ball-cup is held in place. The said ball-cup receives the upper end of the crank 60 13, the same being formed with a V-shaped raceway 19 receiving a series of balls 20, also riding upon the inner face of the ball-cup and held in place by means of a race-ring 21, having an inclined face 22 upon which the 65 balls ride, and held in place by the resting of its edge upon the extreme inner edge of the flange 12 of the assembling-cup. This ring as thus arranged couples the head and crank with freedom of relative rotation. 70

It will be understood that after the parts above described are assembled, the edge 14 of the assembling-cup is spun into the groove 15 of the head 16, whereby the several parts are held together in operative 75 relationship.

In the modification shown by Figs. 9 and 10, the construction above described is altered in so far as the flange 23 of the sleeve 24 is formed with screw holes 25 for the reception of screws 26 which are entered directly into the wooden body 27. The only difference between the two constructions is that in the modified construction screws 26 are employed for securing the body in place 85 instead of spinning the flange of the assembling-cup into a groove in the body. 80

I claim:

In a brace head, the combination with a one-piece, sheet-metal assembling-cup comprising a sleeve and an annular flange concentric therewith and offsetting therefrom at substantially a right angle thereto, of a body fastened to said flange and formed in its inner face with a concentric chamber, an inverted ball-cup located within the said chamber and resting upon the said flange by which it is held in place in the said chamber, a crank having its upper end entered into the said ball-cup and formed with a raceway, 90 antifriction balls interposed between the said ball-cup and raceway, and a race-ring formed independently of the assembling-cup and ball-cup and inserted within the open 95 100 105

end of the latter for co-action with the said balls and for holding the crank in place within the ball-cup, the outer edge of the said race-ring resting upon the flange of the 5 assembling-cup at the juncture of the said flange with the sleeve of the said cup.

In testimony whereof, I have signed this

specification in the presence of two subscribing witnesses.

EDWIN W. BULLARD.
